US00D764943S

(12) **United States Design Patent** (10) **Patent No.:** **US D764,943 S**
(45) **Date of Patent:** **** Aug. 30, 2016**

(54) **CATHETER PACKAGE**

(71) Applicant: **Hollister Incorporated**, Libertyville, IL (US)

(72) Inventors: **Michael Murray**, Ballina (IE); **Martin McMenamin**, Lifford (IE); **Brendan Heneghan**, Louisburgh (IE); **Adam Foley**, Swords (IE)

(73) Assignee: **Hollister Incorporated**, Libertyville, IL (US)

(**) Term: **14 Years**

(21) Appl. No.: **29/492,949**

(22) Filed: **Jun. 4, 2014**

(51) LOC (10) Cl. **09-05**

(52) U.S. Cl.

USPC **D9/707**

(58) **Field of Classification Search**

USPC 206/571, 219; 604/328, 346, 327, 329, 604/330, 408, 317, 349, 265, 171, 262, 414, 604/415; D9/702-714, 414, 424, 426, D9/430-432; D24/118, 122; 4/144.4; 128/DIG. 24

(57) **CLAIM**

The ornamental design for a catheter package, as shown and described.

DESCRIPTION

FIG. 1 is a front perspective view of a catheter package, showing the new design;

FIG. 2 is another front perspective view of the catheter package of FIG. 1;

FIG. 3 is a rear perspective view of the catheter package of FIG. 1;

FIG. 4 is another rear perspective view of the catheter package of FIG. 1;

FIG. 5 is a front elevational view of the catheter package of FIG. 1;

FIG. 6 is a rear elevational view of the catheter package of FIG. 1;

FIG. 7 is a right side elevational view of the catheter package of FIG. 1;

FIG. 8 is left side elevational view of the catheter package of FIG. 1;

FIG. 9 is a front perspective view of a second embodiment of a catheter package, showing the new design;

FIG. 10 is another front perspective view of the catheter package of FIG. 9;

FIG. 11 is a rear perspective view of the catheter package of FIG. 9;

FIG. 12 is another rear perspective view of the catheter package of FIG. 9;

FIG. 13 is a front elevational view of the catheter package of FIG. 9;

FIG. 14 is a rear elevational view of the catheter package of FIG. 9;

FIG. 15 is a right side elevational view of the catheter package of FIG. 9; and,

FIG. 16 is left side elevational view of the catheter package of FIG. 9.

1 Claim, 8 Drawing Sheets
